UNITED STATES PATENT OFFICE.

ROBERT T. ROMINE, OF MOUNT CLEMENS, MICHIGAN.

BRACING APPARATUS FOR SHEET METAL.

Application filed October 12, 1926. Serial No. 141,132.

This invention relates to an apparatus and method for the shipping or transporting of metal sheets such, for example, as sheet steel, in box cars or other conveyances, and more particularly to an apparatus for binding and supporting a stack of metal sheets on edge upon the car floor so as to prevent relative movement of the sheets in the pack during transit.

Heretofore it has been the conventional practice to pile the sheets in stacks at opposite ends of the car, the sheets in each stack being piled flatwise on the floor of the car against the side walls of the car and thereafter the several stacks being suitably braced at their ends by means of timbers or wooden blocks nailed to the floor of the car. This practice has proved a failure in keeping the stacks intact during transit since the sheets constantly shifted or broke loose as a result of shocks or collisions to which the cars are subjected, and frequently the sheets were driven into the end of the car smashing it and causing great damage to the sheets as well as to the car. In addition the sheets cut into the side walls of the car causing further damage.

When the sheets are stacked in the car with the sheets placed horizontally or flatwise, very serious problems are encountered in attempting to hold the stack of sheets intact as a unit against relative shifting movement of the sheets. The shocks or jolts to which the cars are subjected result in setting up a whipping action of the sheets or in other words the flat pile of metal sheets will bend transversely in the middle and then flatten out with a whip-like action. Where the stack of sheets is buttressed at its ends, the weaving or whipping action, as well as the shifting of the sheets against the buttresses results in crimping the edges of the sheets, rendering them defective.

The present invention provides a relatively simple and inexpensive apparatus and method for packing sheet metal on the car, which can be easily assembled or knocked down and which will overcome the foregoing disadvantages. Two packs of sheets, each weighing preferably approximately ten tons, where the load capacity of the car is forty tons, are placed at each end of the car, and each pack is placed on edge with the plane of the sheets vertical instead of horizontal or flat as was the common practice heretofore. The bottom edges of the sheets

are supported entirely upon wooden sills or cross members which may, if desired, be nailed to the car floor, and the pack is clamped together by means of a combined bracing, supporting and anti-shifting apparatus. Wood members are drawn or clamped together under pressure against the top and bottom edges of the sheets so that both edges of each sheet will positively tend to cut into the wood and resist longitudinal sliding movement.

Other objects and advantages of this invention will appear in the following description and appended claims, reference being had to the accompanying drawings wherein like reference characters designate corresponding parts in the several views.

Fig. 1 is a side elevation lengthwise of the car showing the pack of metal sheets held edgewise in the bracing and supporting apparatus of this invention.

Fig. 2 is an end elevation of the pack showing the frame structure for maintaining the sheets on edge against a wall of the car.

Fig. 3 is a section taken substantially along the line 3—3, of Fig. 1, showing the adjustable means for gripping the top and bottom edges of the sheets.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. Also it is to be understood that the phraseology or terminology employed therein is for the purpose of description and not of limitation and it is not intended to limit the invention beyond the terms of the several claims hereto appended or the requirements of the prior art.

In the present instance one form of apparatus is illustrated by means of which a pack of metal sheets, such as sheet steel, may be tied or clamped together and supported in position in a freight car for shipment.

A series of wooden sills or cross members 10 are first placed in position upon the floor F of the car and may, if desired, be secured thereto by means of screws 10', or other suitable fastening means, in a position 110 transversely of the car. The pack of metal sheets S is placed in position upon the

wooden members 10 so that the entire weight of the sheets will be carried by these members, the sheets being positioned on edge and extending in a vertical plane as shown in the drawings. The sills are preferably arranged in spaced relation and as many of them may be employed as may be necessary. These sill members are preferably formed of soft wood in order that the lower edges of the sheets comprising the pack S will bite into them, thereby preventing longitudinal shifting of the sheets in the pack.

Each sill member forms the base section of a supporting frame which comprises an upright wooden member 11 preferably secured to the car wall W by means of screws 11', or any other suitable fastening means. An upright wooden member 12 is placed upon the front edge of the sill member 10 and engages the face of the outermost sheet of the pack. An upper wood member 13 extends across the top edges of the sheets transversely of their length, the several members forming a frame structure extending transversely about the pack.

Metallic plates 14, having a series of holes therein, are provided for the purpose of securing the abutting ends of the several horizontal and vertical members of the wooden frame structure together, such plates being secured to the several members by means of screws 14', or any other suitable fastening means. These plates are positioned on opposite sides of the frame members at their meeting faces as illustrated in Figure 1, so as to provide a rigid connecting means for the frame members or sections.

Interposed between the supporting frames are clamping members for firmly gripping the upper and lower edges of the metal sheets. Each of the clamping members comprises a wooden base member or transversely extending sill 15 positioned below the pack and provided adjacent each end with a countersunk recess 15'. A top member 16 extends transversely across the upper edges of the sheets, the member 16 being provided adjacent each end with a vertical hole 16'.

A vertically extending rod 17 provided with a head 17' and an externally screw threaded end 17² is provided for the purpose of drawing together the ends of the members 15 and 16. The head 17' of the rod is positioned within the recess 15' formed in the base member 15 and its upper end extends through the hole 16' in the top cross member 16. A nut is applied to the screw threaded end 17² of the rod and serves to draw the cross members 15 and 16 together. A similarly formed rod is provided for the purpose of drawing together the opposite ends of the members 15 and 16.

It will be seen that when the gripping device

or frame is placed in position about the pack, the wooden members 15 and 16 are drawn together to compress the same against the upper and lower longitudinal edges of the sheets forming the pack S to hold them firmly and rigidly in place.

Any suitable number of supporting frames comprising the parallel horizontal and vertically extending wooden sections may be employed, and likewise any necessary number of clamping members comprising the horizontal wooden frame members and upright rod members, may be employed.

From the foregoing it will be seen that with the use of the present improved apparatus a pack of metal sheets is firmly held on edge against movement relatively to the car floor or walls when the car is in transit. Moreover, the present invention provides a method whereby the sheets are held against shifting by virtue of their own friction against the upper and lower wood members 15 and 16.

It is important to note that by pressing downwardly on the upper edges of the sheets through the medium of members 16 of softer material than the sheets, the desired frictional engagement with the upper edges is obtained, and, furthermore, the downward pressure assists the weight of the sheets in obtaining frictional engagement between the lower edges of the sheets and the members 10 and 15 and holds the sheets in engagement with these members against any tendency to move upwardly therefrom in transit.

What I claim is:

1. An apparatus for bracing a pack of metal sheets on their edges in a freight car, comprising a plurality of frames comprising sections extending transversely about said pack, said sections being detachably connected together, certain of said sections being removably attached to the car floor and wall, and adjustable means extending transversely about said pack interposed between said frame members for additionally supporting said pack and preventing dislodgment of the sheets.

2. In an apparatus for bracing a pack of metal sheets on their edges in a freight car, the combination of a wood member extending transversely beneath the pack engaging the lower edges of the sheets, a wood member extending transversely across the top of the pack engaging the upper edges of the sheets, and means for drawing said members together to compress the same against the opposite edges of the sheets.

3. In an apparatus for bracing a pack of metal sheets on their edges in a freight car, the combination of a wood member extending transversely beneath the pack engaging the lower edges of the sheets, a wood member extending transversely across the top of the pack engaging the upper edges of the sheets.

sheets, means for drawing said members together to compress the same against the opposite edges of the sheets, and a supporting frame comprising upright buttresses at opposite sides of the pack for supporting the sheets on their edges.

4. In an apparatus for bracing a pack of sheet metal supported in the car with the sheets on edges, the combination of a plurality of members extending transversely beneath the pack and having wood surfaces engaging the lower edges of the sheets, a plurality of members extending transversely across the top of the pack and having wood surfaces engaging the upper edges of the sheets, and means for drawing said members together to compress the wood surfaces against the upper and lower edges of the sheets.

5. In an apparatus for bracing a pack of sheet metal supported in the car with the sheets on edges, the combination of a plurality of members extending transversely beneath the pack and having wood surfaces engaging the lower edges of the sheets, a plurality of members extending transversely across the top of the pack and having wood surfaces engaging the upper edges of the sheets, means for drawing said members together to compress the same against the upper and lower edges of the sheets, and a plurality of supporting frames comprising upright buttresses at opposite sides of the pack for supporting the sheets on their edges.

6. In an apparatus for bracing a pack of metal sheets on their edges in a freight car, the combination of a plurality of wood members extending transversely beneath the pack whereby the lower edges of the sheets will bite thereinto, a plurality of wood members extending transversely across the top of the pack engaging the upper edges of the sheets, means for drawing said members together to compress the same against the upper and lower edges of the sheets, and a supporting frame comprising upright buttresses at opposite sides of the pack and parallel horizontal members above and below the pack for supporting the sheets on their edges.

7. An apparatus for bracing a pack of metal sheets on their edges in a freight car comprising a plurality of substantially rectangular frames, each comprising top, bottom and upright side members, means for connecting the adjacent ends of said members, a wood member engaging the upper edges of the sheets, and means for drawing said member downwardly against said edges.

8. An apparatus for bracing a pack of metal sheets on their edges in a freight car comprising frames having parallel vertical and horizontal sections, certain of said sections being removably connected with a wall

of the freight car, upper and lower wooden sections, and vertically extending brace rods connecting said sections for adjusting their relative positions to bind the opposite edges of the sheets.

9. An apparatus for bracing a pack of metal sheets on their edges in a freight car comprising a frame having a base section provided with a wood surface extending transversely beneath the lower edges of the sheets and being detachably connected with the car floor, a rear vertically extending section removably connected with a wall of the car, a front vertical section parallel with the rear section, a top section parallel with the base section, and plates for inter-connecting the several sections at their meeting ends.

10. Means for supporting a pack of metal sheets on their edges in a freight car, comprising a wooden base member extending transversely beneath the lower edges of the sheets, a wooden top member adapted to engage the upper edges of the sheets, and means for adjusting the relative positions of the wooden members to cause their engagement with the upper and lower edges of the sheets.

11. Means for supporting a pack of metal sheets on their edges in a freight car, comprising a wooden base member extending transversely beneath the lower edges of the sheets, having countersunk recesses in its lower face adjacent the ends, a wooden top member provided with holes adjacent each end thereof, and a pair of rods having enlarged heads at one end seated in the said recesses, their opposite ends extending through the holes in the top member and being screw threaded, and nuts applied to said screw threaded ends for adjusting the relative positions of the base and top members whereby said members engage the upper and lower edges of the sheets and prevent their dislodgement from the pack.

12. In an apparatus of the class described, the combination of means for holding together in a unit a pack of metal sheets on the car floor with the sheets mounted on their edges, a member or members extending over the top of the pack and having wood surfaces engaging the upper edges of the sheets, and means for drawing said member or members downwardly against the edges of the sheets.

13. The herein described method of transporting sheet or strip metal supported on edge in a car which consists in pressing members of relatively softer material than the sheets against their upper and lower edges whereby to resist frictionally sliding movement of the sheets in transit.

14. The herein described method of transporting sheet or strip metal supported on edge in a car which consists in pressing members of relatively softer material than

the sheets against their lower and upper edges running lengthwise of the car, whereby to resist frictionally sliding movement of the sheets in transit.

5 15. The herein described method of transporting sheet or strip metal supported on edge in a car which consists in pressing members of relatively softer material than the sheets against their upper edges whereby 10 to resist frictionally sliding movement of the sheets in transit.

16. The herein described method of transporting sheet or strip metal supported on edge in a car which consists in pressing members of relatively softer material than the sheets against their upper edges running lengthwise of the car whereby to resist frictionally sliding movement of the sheets 15 in transit.

20 17. In an apparatus for transporting sheet or strip metal in a pack in a freight car with the sheets resting on edge, means above the upper edges relatively softer than the

sheets engaging said edges, means below the lower edges relatively softer than the sheets 25 adapted to engage frictionally the lower edges, said last mentioned means being exposed for engagement with the floor of a car, and means for pressing both of said means into frictional engagement with the 30 edges of the sheets.

18. In an apparatus for transporting sheet or strip metal in a pack in a freight car with the sheets resting on edge, means above the upper edges relatively softer than the 35 sheets engaging said edges, means below the lower edges relatively softer than the sheets adapted to engage frictionally the lower edges, said last mentioned means being exposed for engagement with the floor of a 40 car, and arranged to support the pack and means for pressing both of said means into frictional engagement with the edges of the sheets.

In testimony whereof I affix my signature.

ROBERT T. ROMINE.
